poration of Illinois

Application November 9, 1945, Serial No. 627,681

10 Claims. (Cl. 121—41)

1

The present invention relates generally to hydraulic power control mechanism and has for its principal object the provision of a novel and improved hydraulic mechanism, which is more sensitively and more accurately controlled than similar mechanism heretofore known to those skilled in the art, and yet which is simple and inexpensive to manufacture and strong and durable in operation.

Another object of the invention relates to the provision of a hydraulic power control mechanism having a manually adjustable control lever for controlling the movement of the mechanism in either direction, the operation of which is closely similar to that of an ordinary manually controlled lever connected directly to a load. In this type of hydraulic system, the control lever is moved by the operator in one direction or the other, depending upon which direction he desires to move the load. The control lever moves at a rate which is proportional to the speed of movement of the load and as long as the operator exerts a small amount of force against the control lever, while the load is being moved by a hydraulic motor. When the operator releases pressure from the control lever, the motor as well as the control lever stops immediately. Thus, the operation of the control lever in this type of hydraulic system is similar to the movement of an ordinary hand lever connected directly to the load, which moves as long as the operator exerts pressure against it but stops immediately upon release. The only difference in operation is that the actual force required to move the load is exerted by a separate source of power, rather than by the actual pressure exerted by the operator.

A system of this type is valuable for the purpose of adjusting agricultural implements associated with a tractor, inasmuch as operators of this type of equipment are familiar with the operation of ordinary hand adjusting levers, so that a hydraulic mechanism of this type requires practically no additional training in its operation.

Under certain operating conditions, such as when adjusting the operating position of a tractor mounted implement, it is desirable to have the hydraulic motor operate slowly in order to facilitate an accurate adjustment of the implement, but under other conditions, such as when raising the implement to a transport position, it is desirable to have the hydraulic mechanism operate as quickly as possible. Another object of the present invention, therefore, relates to the provision of means for controlling the speed of response of the hydraulic motor.

2

A further object relates to the provision of means whereby the operator is not required to maintain pressure on the control lever when he desires the implement to move in either direction to the extreme end of the range of movement of the hydraulic motor. This feature is valuable for the purpose of raising the implement to transport position when the tractor reaches the end of the field, for at such times the operator is busy turning the tractor around at the end of a row or furrow and steering it into alignment with the next row or furrow. In the accomplishment of this object, the control lever is provided with latching means, which holds the control valve in active position to cause the hydraulic motor to operate, but without affecting the movement of the control lever proportional to the movement of the load.

A related object has to do with the provision of adjustable stop means against which the control lever engages, when it is being moved to shift the position of a load, the engagement of the lever with the stop thereby causing the control valve to stop the movement of the hydraulic motor and thus to arrest the movement of the load at any particular predetermined position. This feature is valuable in insuring that the implement will always be returned to the predetermined working depth after the tractor has been turned around at the end of the field, and this feature is operative either while the operator is maintaining a pressure against the control lever, or when the lever is latched in its active position.

Still another object of the present invention relates to the provision for automatically unlatching the control lever and stopping the hydraulic motor at any point in case the pressure in the hydraulic system increases above a predetermined maximum, such as when the implement may encounter an obstruction during its movement by the hydraulic motor. In the accomplishment of this object, the mechanism which latches the control valve in active position is connected with the excess pressure relief valve in such a manner that an actuation of the relief valve unlatches the latching mechanism.

These and other objects and advantages of the present invention will be apparent to those skilled in the art after a consideration of the following description, in which reference is had to the drawings appended hereto, in which:

Figure 1 is a rear elevational view of the central portion of a tractor rear axle housing, showing hydraulic power control mechanism embodying the principles of the present invention;

Figure 2 is a sectional elevational view taken

along a fore and aft extending vertical plane indicated by a line 2—2 in Figure 1;

Figure 3 is a sectional plan view taken through the hydraulic control valve housing along a line 3—3 in Figures 2 and 4, and drawn to an enlarged scale;

Figure 4 is an elevational view taken along a line 4—4 in Figures 2 and 3;

Figure 5 is a sectional elevational view taken along a line 5—5 in Figure 3;

Figure 6 is a sectional elevational view taken along a line 6—6 in Figure 3;

Figure 7 is a view similar to Figure 6 but showing the valve mechanism in latched position in one direction of operation;

Figure 8 is a fragmentary elevational view of the latch mechanism as in Figure 7, but with the control lever and valve latched in the opposite direction; and

Figures 9 and 10 are sectional elevational views of the control valve mechanism taken along a line 9—9 in Figure 4 and drawn to an enlarged scale, and show four different positions of the control valve mechanism during operation.

Referring now to the drawings, and more particularly to Figures 1 and 2, the tractor is indicated by a portion of its body including a banjo-type rear axle housing 20, comprising an enlarged centrally disposed gear housing 21 and a pair of oppositely extending axle housing quills 22 formed integrally therewith. The quills 22 contain a pair of coaxially disposed drive axles 23, the inner ends of which carry drive gears 24 disposed within the gear housing portion 21, and the drive gears 24 are driven from the engine of the tractor by suitable mechanism, the details of which are not shown since they are well known to those skilled in the art. The gear compartment 21 of the axle housing 20 is provided with a large opening 25 in the rear side thereof, which opening is covered by a large housing or cover 26 having an outwardly turned flange 27 extending peripherally around the housing 26 and secured to the gear compartment 21 by bolts 28. The housing 26 is integrally formed with a transversely disposed bearing sleeve 29 in the upper portion thereof within which is journaled a conventional rockshaft 30, the two ends 31 of which extend laterally from the ends of the sleeve portion 29 and are of substantially square cross section for the purpose of receiving implement controlling and lifting arms (not shown), as is well known to those skilled in the art.

The rockshaft 30 is actuated by a rocker arm 35 fixed to a hub 36 secured to the rockshaft 30. The rocker arm 35 extends downwardly and is pivotally connected by a pin 37 to a piston rod 38. The piston rod 38 extends forwardly and is connected to the piston 39 of a fluid pressure motor 40 by means of a wrist pin 41. The fluid pressure motor 40 comprises the piston 39 and a cylinder 42, within which the piston is slidably. A fluid supply duct 43 is formed integrally with the cylinder 42 and extends axially along the lower side thereof for supplying fluid under pressure to the cylinder, the forward end of which is closed by an integrally formed cylinder head 44. The cylinder 42 is positioned between the two axle drive gears 24 and is secured to the front side of the housing 26, the latter having a duct 45 formed integrally therewith in register with the cylinder duct 43.

The construction so far described is identical with the hydraulic mechanism disclosed in Pat-

ent 2,302,637 granted November 17, 1942, to McCormick and Hansen, to which reference may be had for a more complete description of this part of the apparatus. As in the patented structure, the housing 26 also includes an integrally formed reservoir 46 for the hydraulic fluid and also a conventional gear pump indicated generally by reference numeral 47, which is secured by bolts 48 to the rear side of the housing 25. One of the pump gears (not shown) is mounted on the tractor power take-off shaft 49, which extends rearwardly from a suitable connection with the tractor engine and is journaled in a bearing 50 beneath the reservoir 46 and formed integrally with the housing 25. The power takeoff shaft 49 extends rearwardly through the pump 47 and has a splined rear end portion 51 for supplying power to implements associated with a tractor, in a manner well known to those skilled in the art. The pump 47 receives fluid from the reservoir 46 and discharges the same under pressure through a high pressure duct 52 extending upwardly through the reservoir 46, as disclosed in the above-mentioned patent.

Coming now to that portion of the apparatus with which this invention is particularly concerned, a control housing 60 is secured to the rear side of the rockshaft housing 26 by means of a plurality of bolts 61, which extend through apertures 62 in the control housing 60 and engage suitable threaded apertures (not shown) in the housing 26. The control housing 60 is provided with an opening 63 in its forward side, which is disposed in register with a corresponding opening 63' in the rear side of the housing 25, thereby communicating with the reservoir 46 in the latter.

Although the control valve mechanism and its details of construction and operation form no part of this invention, except generally in combination with other elements of the system as defined in the appended claims, a rather detailed description thereof is deemed necessary to a thorough understanding of that phase of the invention disclosed and claimed here. The valve mechanism is disclosed and claimed in co-pending divisional application, Serial No. 785,026, filed November 10, 1947, now Patent No. 2,505,527.

The control housing 60 is provided with a cored high pressure passage 64 provided with an intake port 65. The passage 64 extends upwardly from the port 65 and turns laterally, as indicated at 66 (see Figure 3). The passage 66 turns rearwardly at 67 and again laterally at 68, from which it divides into two branches curving upwardly and downwardly toward the rear of the housing 60, as indicated at 69 and 70, best shown in Figure 5. The two branches 69 and 70 terminate in a pair of annular ports 71, 72 in a vertically extending cylindrical valve chamber 77. The valve cylinder 77 is also provided with a pair of annular exhaust ports 73, 74 spaced from the supply ports 71, 72, respectively. The exhaust ports 73, 74 are connected in communication with the interior of the housing 60, and hence with the reservoir 46. Between each pair of adjacent supply and exhaust ports 71, 73, and 72, 74 is a motor supply port 75, 76, respectively.

A valve member 80 in the form of a generally cylindrical plunger is slidably disposed within the valve cylinder 77. The plunger fits closely within the cylinder to prevent flow of hydraulic fluid along the valve cylinder 77 but is reduced in diameter at two axially spaced regions 81, 82, thereby defining three spool or piston portions 83,

84, 85. When the valve plunger 80 is in its centered neutral or inactive position, shown in Figures 4 and 5, the central piston portion 84 extends between the two fluid supply ports 71, 72, while the portions 81, 82 of reduced diameter extend between the supply ports 71, 72 and the adjacent exhaust ports 73, 74, providing clearance for the hydraulic fluid to flow from each of the branches 69, 70 along the reduced diameter portions 81, 82 and out through the exhaust ports 73, 74, returning to the reservoir 46.

The valve plunger 80 can be shifted upwardly in the valve cylinder 77 until the lower piston portion 85 blocks the valve cylinder above the lower exhaust port 74, thereby preventing escape of the fluid from the branch duct 70, while the center piston 84 moves into blocking relation in the upper supply port 71, preventing the flow of fluid through the upper branch duct 69, thereby directing the fluid from the pump into the lower motor supply port 76, and connecting the upper motor supply port 75 with the exhaust port 73. Conversely, when the valve plunger 80 is shifted downwardly in the cylinder 77, the upper piston portion 83 closes the exhaust port 73, preventing fluid from flowing upwardly from the upper branch duct 69, whereupon the fluid is directed into the upper motor supply port 75. Simultaneously, the lower edge of the central piston portion 84 blocks the lower branch duct 70, while the lower motor supply port 76 is connected with the lower exhaust port 74.

A pair of closure members 90, 91 are positioned in the valve cylinder 77 outwardly of the exhaust ports 73, 74, respectively, defining compartments 92, 93 outwardly of the valve plunger 80 and of slightly larger diameter than the valve cylinder 77. The closure members 90, 91 are pressed tightly into the ends of the compartments 92, 93 to prevent any relative movement thereafter. Each of the closure members comprises a head portion 95 which is pressed into the compartment 92 or 93, and a shank portion 96, which extends into the valve cylinder 77 into telescoping relation with the adjacent end of the valve plunger 80, the latter being provided with an axially extending passage as will be described later in more detail. Each of the closure members 90, 91 is also provided with a drilled opening 97 extending axially therethrough to receive the stem 98 of a poppet type check valve, of which there are two provided, 99, 100, at opposite ends of the valve mechanism, respectively. Each of the check valves 99, 100 is seated in an annular seating member 101, which is pressed into a suitable recess in outwardly spaced relation to the adjacent closure member 90 or 91 to define the outer end of the compartment 92 or 93, respectively. Each of the check valves 99, 100 is urged into engagement with its seat 101 by means of a compression spring 105, disposed in upper and lower check valve chambers 106, 107 and reacts against a plug 108. The two plugs 108 are threaded into the upper and lower ends of the vertical passageway through the housing casting 60, which forms the valve cylinder 77, the compartments 92, 93, and the check valve chambers 106, 107. Each of the compartments 92, 93 is connected with the adjacent motor supply port 75, 76 by means of a by-pass duct 109, 110, respectively, the by-pass ducts serving to convey hydraulic fluid from the valve cylinder 77, around the exhaust ports 73, 74 to the compartments 92, 93, respectively.

The hydraulic mechanism disclosed herein can be used for either of two purposes. First, it

can be used to control the rockshaft 30 by means of the integral cylinder 40 or second, it can be used to control a remotely disposed fluid motor indicated generally by reference numeral 115 in Figure 5. The fluid motor 115 comprises a cylinder 116 and a piston 117 slidably axially therein and connected to an actuating rod 118 which extends outwardly through a packing gland 119 in the closed end of the cylinder. A connector 120 is provided on the end of the piston rod 118 for connecting the latter to implements associated with the tractor. The opposite end of the cylinder 116 is also closed by means of a cylinder head 124, which is formed integrally with a mounting lug 125 provided for attaching the cylinder to the associated implement. The fluid motor 115 is of the double-acting type, which provides for fluid to be conducted under pressure into either end of the cylinder for the purpose of forcing the piston 117 in either direction within the cylinder 116. The head 124 is provided with a fitting 126 for introducing fluid under pressure into one end of the cylinder, while another fitting 127 is provided for introducing fluid under pressure into a duct 128 formed integrally with the cylinder 116 and extending axially along the latter and communicating with the opposite end of the cylinder bore. Each of the fittings 126, 127 is provided with a flexible hose 129, 130, the two hoses being detachably connected with the hydraulic control mechanism by means of a pair of bayonet connectors 133, 134.

Each of the connectors 133, 134 comprises a tubular member 135 adapted to be slidably insertable into upper and lower horizontal passages 136 in the rear wall of the control housing 60, into the valve chambers 106, 107, respectively. An annular sealing member 137 is provided for sealing each of the passages 136 against leakage of oil therefrom, each of the sealing members 137 being disposed within a cylindrical neck 138 which is rigid with the housing 60 and is externally threaded to receive a clamping collar 139 which has an inwardly turned securing flange 140. The tubular member 135 is provided with a head 143 which is circumferentially grooved at 144 to receive a segmental or split washer 145, which is adapted to be clamped between the collar 139 and the end of the neck 138, to hold the connector 135 within its socket. The washer 145 can be made of frangible material, so that it will break in the event that the draft connection between the implement and the tractor is broken and an attempt is made to move the tractor away from the implement without disconnecting the motor 115 from the implement or from the housing 60.

It will now be evident to those skilled in the art that when the valve plunger 80 is shifted upwardly in the valve cylinder 77 the central piston portion 84 closes off the upper fluid supply port 71 and directs fluid under pressure from the lower supply port 72 downwardly through the motor supply port 76 and the by-pass duct 110 to the compartment 93, in which the pressure of the oil forces open the lower check valve 100, whereupon the oil flows past the valve 100 through the tubular member 135 of the lower connector 133, and then through the flexible hose 129, causing the cylinder and piston rod 118 to be extended. This forces the oil out of the opposite end of the cylinder 116 through the duct 128, flexible hose 130, and connector 134 to the upper check valve chamber 106. The upper check valve 99 has been raised away from its seat 101 by upward movement of the valve plunger 80, in a manner to be described

7 later, whereupon the fluid returning from the cylinder 116 passes under the open check valve 99, through the by-pass duct 109 and port 75 into the valve cylinder 77 and along the reduced diameter portion 81 of the plunger 80 into the upper exhaust port 73 and thus returned to the reservoir.

Conversely, the piston 117 can be shifted in the opposite direction within the cylinder 116 by moving the valve plunger 80 downwardly within the valve cylinder 77, thereby directing fluid from the upper supply port 71 to the upper motor supply port 75, up through the by-pass duct 109, through the upper check valve 99 and hose 130 to the lower end of the cylinder 116, as viewed in Figure 5. Movement of the piston 117 upwardly within the cylinder 116 forces fluid through the hose 129, connector 133, and upwardly through the lower check valve 100, which is opened responsive to downward movement of the valve plunger 80 in the valve cylinder 77, as will be explained. The fluid then flows upwardly through the by-pass duct 110 and supply port 76, back to the reservoir through the lower exhaust port 74.

The single acting hydraulic motor 40 is connected through the supply ducts 43, 45 through a passage 150, which is formed integrally with the control housing 60 and communicates with the lower check valve chamber 107. A shut off valve 151 is provided in the passage 150, and can be of any suitable form such as a vertical cylindrical member 152 extending upwardly through the passage 150 and journaled above and below the latter, the member 152 being adapted to completely block the passage 150 but having a diametrically extending aperture 153 which, as shown in Figure 5, is positioned transversely of the passage 150, wherefore the latter is blocked by the cylindrical member 152, but when the member 152 is turned through an angle of 90 degrees, the aperture 153 is aligned with the passage 150 and conducts the fluid therethrough. The cylindrical member 152 is provided with a head 154 beneath the housing 60 for the purpose of turning the cylinder 152 to open or close the valve, and the upper end of the valve member 151 is provided with a threaded end portion 155 of reduced diameter, which is adapted to receive a nut 156 for securing the valve member 151 in position. Sealing washers 157 prevent leakage of oil out of the passage 150 along the valve member 151.

When the double acting remote cylinder 115 is connected to the control housing 60, the shut off valve 151 is positioned with the aperture 153 transversely of the passage 150 in order to prevent flow of fluid to the integral cylinder 40. However, when it is desired to operate the rock-shaft 30 by means of the integral cylinder 40, the remote cylinder 115 should be disconnected by unscrewing the two collars 139 and withdrawing the connectors 133, 134. The passages 136 should then be closed to prevent oil from flowing out through the necks 138 by any suitable means, such as by closure caps 158, shown in Figures 1, 2, 3, 6 and 7. The valve 151 should then be opened by turning the cylindrical member 152 to align the aperture 153 with the duct 150.

The piston 39 in the integral cylinder 42 is forced rearwardly by pressure within the latter, responsive to an upward movement of the valve plunger 80, which directs fluid from the lower branch 70 and supply port 72 downwardly through the lower check valve 100 and along the

8 passages 150, 45, and 43, to the cylinder 42. Likewise, to lower the implement, the valve plunger 80 is shifted downwardly within the valve cylinder 77, to open the lower check valve 100 and allow the fluid to flow from the cylinder 42 upwardly through the by-pass duct 110 and port 76, to be released through the exhaust port 74 to the reservoir.

While the oil is being returned from the cylinder 42 to the reservoir, the fluid output of the pump 47 is being directed upwardly through the upper branch 69 of the supply duct, through the upper supply port 75 and by-pass duct 109 into the compartment 92. The pressure of the fluid forces open the check valve 99, permitting the oil to flow into the check valve chamber 106. Provision is made for returning the fluid from the check valve chamber 106 to the reservoir, inasmuch as the closure cap 158 prevents flow of fluid out through the neck 138, and this provision takes the form of a vertical return duct 159, which intersects the horizontal passage 136 intermediate the ends of the latter and extends downwardly therefrom. The lower end of the return duct 159 intersects the lower horizontal passage 136, thereby returning the fluid from the pump to the lower check valve chamber 107, where it joins the flow from the integral cylinder 42 and is returned through the exhaust port 74 to the reservoir. A check valve 160 is disposed within the duct 159 and is urged upwardly by means of a compression spring 161 to a seat 162 within the duct 159, thereby preventing any flow of fluid upwardly through the passage 159 when the piston 39 is being forced rearwardly in the integral cylinder 42 under pressure. The check valve 160 is opened however by fluid flowing down through the passage 159 during the return movement of the piston 39 forwardly in the cylinder 42.

It will be noted that the tubular connectors 135 close off both ends of the passage 159 while the double acting motor 115 is being used. The upper and lower ends of the passage 159 are closed by plugs 163, 164, respectively. The reactive force of the compression spring 161 is taken on a snap ring 165 seated in the wall of the passage above the connector 135.

The valve plunger 80 is shifted upwardly and downwardly within the valve cylinder 77 by means of a gear member 170 rotatably disposed within a cylindrical chamber 171 between the two branches 69, 70 of the supply duct 68. The chamber 171 intersects the vertical valve cylinder 77 and the gear member 170 is provided with teeth along one side of the periphery thereof, which extend into the valve cylinder 77 and mesh with a short rack 172 formed in the central piston portion 84 of the valve plunger. Thus, by rotating the gear member 170 through a limited angle in either direction from a central neutral position, the valve plunger 80 can be shifted upwardly or downwardly within the cylinder 77 to its active positions for controlling the fluid motor associated therewith. The gear member 170 has an end portion 173 of reduced diameter which extends laterally out of one end of the cylindrical passage 171, as is best shown in Figure 3. A hub 174 is fixed on the spindle portion 173 of reduced diameter and is formed integrally with a rearwardly extending actuating arm 175. The arm 175 is connected by a pivot pin 176 to a link 177 which extends upwardly therefrom and is pivoted at 178 to a crank arm 179, which is rigidly mounted on a shaft 180, which is jour-

naled in a cylindrical bearing member 181 in offset relation from the axis of the latter. The cylindrical bearing member 181 is journaled for rotation about its axis in a cylindrical socket 182 formed integrally with the housing casting 60, as best shown in Figure 5. The shaft 180 extends outwardly through the bearing member 181 and carries a manually actuated control lever 183 rigidly fixed thereto. The bearing member 181 is connected by means of a link 184 to the rocker arm 35 by means of a pivot pin 186. The rear end of the link is pivoted at 187 to the bearing member 181 at a point spaced from the axis of rotation of the latter.

Thus it will be evident that by swinging the control lever 183 forwardly or rearwardly, the shaft 180 and arm 179 can be rocked to raise and lower the outer end of the actuating arm 175 and gear member 170, thereby raising and lowering the valve plunger 80.

When the double acting remote cylinder 115 is connected for operation by the hydraulic mechanism, the integral cylinder 40 is locked, inasmuch as the shut off valve 151 is closed to prevent flow of oil into or out of the cylinder 42, with the result that the bearing member 181 is held against rotation in its socket 182.

However, when the integral fluid motor 40 is being operated by the hydraulic mechanism, it is evident that when the control lever 183 is swung forwardly to raise the valve plunger 80, thereby directing fluid under pressure into the cylinder 42 to force the piston 39 rearwardly, the rocker arm 35 and rockshaft are moved in a counter clockwise direction about the axis of the rockshaft 30 (as viewed in Figures 2, 6, 7 and 8), thereby acting through the link 184 to rotate the bearing member 181 in a counterclockwise direction. This moves the shaft 180 downwardly and rearwardly, carrying with it the control lever 183, with the result that if the operator continues to exert a forward pressure on the control lever 183, the latter will gradually move forwardly as long as the valve plunger 80 is held in a raised position. The fact that the operator may feel the downward movement of the lever 183 is of little importance, since such movement is but slight and is not incompatible with the forward movement of the lever as initiated by him. Whenever the operator releases the control lever 183, the actuating arm 175 and the gear member 170 are returned to the neutral position by a resilient centering device, indicated generally by reference numeral 190, which will be described presently. Of course it will be understood that centering the actuating arm 175 and the valve member 80 immediately stops the movement of the piston 39 in the cylinder 42.

Conversely, when the operator swings the control lever 183 rearwardly, the shaft 180 and arm 179 are swung downwardly, thereby swinging the actuating arm 175 downwardly to shift the valve plunger 80 downwardly to open the lower check valve 100 and allow the fluid to be forced out of the cylinder 42 by the weight of the load acting against the piston 39. As the piston 39 moves forwardly within the cylinder 42, the rocker arm 35 swings forwardly and acts through the link 184 to turn the bearing member 181 in a clockwise direction, and as long as the operator exerts a pressure against the control 183 to resist the resilient centering device 190, the piston 39 continues to move forwardly and the control lever 183 moves rearwardly with the bearing member 181 as the latter turns about its axis of rotation.

At the same time, the lower end of the lever 183 is moving slightly upwardly and forwardly because rotation of the bearing member 181 effects slight displacement of the shaft 180 in those directions. Even though this movement may be felt by the operator, it will not disturb either him or the operation of the mechanism, since such movement is concomitant to rearward movement of the control lever. As before, when the operator releases the lever 183 the centering device 190 centers the valve plunger 80 and stops the movement of the piston 39.

Thus it is evident that the action of the control lever 183 is similar to the action of an ordinary operating lever on an implement, since the lever moves with the implement under pressure exerted by the operator, with the exception that the operator need only exert enough pressure to overcome the resilient centering device while the hydraulic motor 40 furnishes the power necessary to move the implement connected to the rock-shaft 30. Furthermore, as with a direct connected lever, the movement of the implement stops as soon as the operator releases the lever. There is, however, a slight backward movement of the control lever 183 due to the centering of the actuating arm 175 under the action of the resilient centering device 190, when the operator releases his hold on the lever 183.

The resilient centering device comprises a pair of arms 191, 192, which are pivotally mounted on the pivot pin 176 on the end of the actuating arm 175. The arms 191, 192 extend forwardly on opposite sides of the stub shaft or spindle 173 on the valve operating gear member 170. Each of the arms 191, 192 is provided with an arcuate notch 193, best shown in Figures 7 and 8, for receiving therebetween the stub shaft 173. The arms 191, 192 are also formed with integral opposed ears 194, which are interconnected by a helical tension spring 195 tending to hold the arms 191, 192 in gripping relation on the stub shaft 173. The inner edges of the arms 191, 192 are also provided with a second pair of opposed arcuate notches 196 near the outer ends of the arms 191, 192, which are adapted to engage a latch pin 197.

The latch pin 197 is mounted on an excess pressure relief valve member 200, which is axially slideable in a cylindrical passage 201 in the control housing casting 60. The valve member 200 is of the poppet type and is adapted to seat in a port 202 communicating with the pump discharge duct 64. The stem 203 of the poppet valve 200 extends through an aperture 204 in the wall of the duct 64 and is provided with a nut 205 on the threaded outer end of the stem. A compression spring 206 acts between the nut 205 and the wall of the duct 64 to yieldably hold the valve 200 in closed position. The valve 200 is provided with a plurality of axially extending grooves 207, which terminate short of the end of the passage 201. Thus, when the pressure of the fluid in the duct 64 exceeds the pressure of the spring 206, which can be adjusted by means of the nut 205, the valve 200 is forced away from its seat 202, but since it fits closely within the passage 201 the oil cannot escape until the ends of the grooves 207 move outwardly of the passage 201. Hence, the valve 200 must move an appreciable distance away from its seat 202 before relief is provided, thereby preventing vibration of the valve member against the seat.

The latch pin 197 is mounted between a pair of axially extending legs 208 on the end of the valve member 200, and the two pivoted arms 191,

132 extend between the legs 208 in gripping relation on opposite sides of the pin 197. When the valve plunger 80 is in its neutral or inactive position, the arms 191, 192 grip the pin 197, as shown in Figure 6, near the outer ends of the arms outwardly of the notches 196. When the control lever 183 is moved rearwardly to adjust the implement downwardly, the arm pivot 176 is moved downwardly with the valve actuating arm 175 about the axis of the stub shaft 173 and gear member 170. The upper arm 191 is free to swing angularly about the axis of the shaft 173, but the lower arm 192 is prevented by the latch pin 197 from swinging about the axis of the shaft 173, as will be evident in Figure 7. This causes the arms 191, 192 to be spread apart against the pressure of the tension spring 195, with the result that when the lever 183 is released, the spring 195 acts to close the arms 191, 192, thereby swinging the pivot pin 176 upwardly and returning the valve and the control lever 183 to the neutral position.

Similarly, when the control lever 183 is actuated forwardly from neutral position, the lower arm 192 swings about the stub shaft 173 out of engagement with the latch pin 197, while the upper arm 191 bears against the latch pin 197 and is separated from the lower arm 192 against the action of the spring 195. Hence, it will be evident that the centering device 190 acts by the force of the spring 195 to return the valve member 80 and control lever 183 to neutral or inactive position from either direction of actuation.

If the lever 183 is shifted in either direction to actuate the valve member 80 to its extreme position, the latch pin 197 receives the outer notch 196 in the arm with which it is engaged. This causes the control lever 183 and the valve member 80 to be retained in the extreme position after the operator has released the control lever. This is desirable in cases where the implement is to be raised or lowered to the end of the stroke of the piston 39, thereby relieving the operator of the necessity for holding the control lever until the implement is completely raised or lowered. However, the operator can easily disengage the latch pin 197 from the notch 196 at any time.

The temporary retention of the parts in the positions shown in Figure 8, for example, is accomplished as follows, all references to right and left hand sides and directions of movement being made with respect to Figures 2, 6, 7 and 8: Fundamentally, the pin 173 is fixed. The pin 197 is fixed, except when displaced to the right by operation of the pressure relief valve 200, which result may be disregarded for the moment; hence, the distance between 173 and 197 is normally fixed. The distance between the pin 176 and the pin 173 is fixed by the arm 175. On the other hand, the distance between the pin 176 and the pin 197 is variable as the pin 176 moves in its arcuate path about 173.

When the parts are in neutral positions (Figures 2 and 6), the extreme left hand ends of the arms 191 and 192 rest respectively on diametrically opposed upper and lower sides of the pin 197, and the notches 193 in the arms engage the pin 173, the arms being urged together by the spring 195. Assume now that the lever 183 is rocked forwardly short of its extreme position: The link 177 will move the pin 176 upwardly, thus shortening the distance between 176 and 197; and the left hand end of the arm 191 rides forwardly on the top of the pin 197. The parts are now approaching the positions of Figure 8

and the notch 196 in the upper arm 191 has not yet engaged the pin 197. Hence, the parts are not yet latched and the spring 195 can return them to neutral.

However, continued forward rocking of the lever 183 results in continued upward movement of the pin 176, further shortening the distance between 176 and 197. Consequently, the notch 196 in the upper arm 191 now engages the pin 197 and fixes the distance between 176 and 197. The distance between 173 and 197, as aforesaid. Therefore, we have a temporarily rigid triangle 197-176-173, the structure of which depends on the notch 196 of the upper arm 191 and action of the spring 195.

It will be seen, now, that any tendency of the pin 176 to move downwardly would result in a tendency to increase the distance between 176 and 197, which result is resisted by engagement of the notch 196 of the upper arm 191 with the pin 197. Collapse of the temporary triangle is otherwise opposed by the fixed distance between 176 and 173 and the normally fixed distance between 173 and 197. The operator may, at will, destroy the triangle by moving the lever 183 rearwardly, thus forcing the notch 196 in the arm 191 to release its hold on the pin 197. As will hereinafter appear, operation of the pressure relief valve 200 to shift the pin 197 will also effect collapse of the triangle.

When the integral fluid motor 40 is being controlled, provision is made for automatically returning the control lever 183 to neutral position when the implement reaches a predetermined position during movement in either direction. Referring to Figure 2, a guide plate 212 is mounted rigidly on the tractor adjacent the control lever 183 and is provided with an arcuate slot 213, in which are secured a pair of adjustable limit stops 214, 215 in the form of bolts extending through the slot 213 and having thumb nuts for tightening the bolts in any position of adjustment along the slot 213. The stops 214, 215 are adapted to engage the control lever 183 as the latter is shifted angularly by rotation of the bearing member 181 as it is rotated by the link 184. After the control lever 183 has engaged one of the stops 214 or 215, further movement of the bearing member 181 causes the actuating arm 175 and valve member 80 to be returned to neutral position, thereby arresting movement of the piston 39. For example, assume that the operator swings the control lever 183 forwardly until the notch 196 in the upper arm 191 of the centering device 190 engages the latch pin 197, as in Figure 8. This causes the piston 39 to be moved rearwardly in the cylinder 43, shifting the rocker arm 35 in a counterclockwise direction, as viewed in Figure 2, with a similar movement of the bearing member 181, carrying the shaft 180 downwardly and rearwardly and swinging the control lever 183 forwardly until it engages the forward stop 214 in the slot 213. Continued movement of the piston 39 rearwardly, with the lever 183 against the stop 214, tends to move the lever 183 rearwardly about the axis of its supporting shaft 180, thereby disengaging the notch 196 in the arm 191 from the latch pin 197, whereupon the spring 195 returns the valve member 80 to neutral position. The control lever 183 is now inclined forwardly adjacent the forward stop 214 but has been retracted slightly rearwardly therefrom by the centering action of the spring 195. The con-

trol lever 183 can now be actuated rearwardly to cause the lower arm 192 to move into latching engagement with the latch pin 197, whereupon the piston 39 will move forwardly in the cylinder 42, acting through the link 184 to swing the bearing member 181 in a clockwise direction, and thereby swinging the control lever 183 rearwardly until it engages the rear stop 215, after which further movement of the bearing member 181 disengages the notch 196 from the latch pin 197, permitting the spring 195 to center the valve member 80.

Normally, the stop 214 would not be used for limiting the raising movement of the implement, for it is customary to raise the implement to the full extent of movement of the rockshaft 30 for transport purposes. However, it is desirable to limit the extent of downward movement of the implement, for example, to control the depth of operation of a cultivator or plow. At the end of each row or furrow the implement must be raised to permit the tractor to be turned, after which the implement is again lowered to the ground engaging position. Thus, by setting the stop 215 in the appropriate position in the slot 213, the implement will always be returned to the predetermined working position, although the latter can be changed easily at any time by shifting the stop 215 along the slot 213.

When the piston 39 is allowed to be forced under pressure to the extreme end of its range of movement, the rear end of the piston rod 38 engages the wall of the duct 64 in the housing casting 60, thereby causing the pressure to rise in the hydraulic system. This increased pressure forces the relief valve 200 rearwardly away from its seat, and since the latch pin 197 is mounted on the valve member 200, the pin 197 is shifted relative to the notch 196, whereupon the spring 195 causes the centering device 190 to shift the valve member 80 to neutral position. Specifically, this result is achieved as follows, reference being had now to Figure 7: As previously stated, the locking of the mechanism results from the temporary triangle defined by 197, 176 and 173, the lock depending in part on fixing the distance between 197 and 176. When the pin 197 is moved to the right, it unseats from the notch 196 in the arm 192 and the distance between 197 and 176 is no longer fixed. The arm 192 then fulcrums on the shifted pin 197 at a point to the right of the notch 196. As the pin 197 moves to the right out of the notch 196, it cams the arm 192 downwardly, adding to the existing tendency of the spring 195 to pull down on the arm 191, and pivoting said arm in a counterclockwise direction about 173 to raise the pin 176—the natural pivot for the parts. At the same time, the pin 197, in leaving the notch, also exerts a rearward push on 192 which further tends to raise 176. The parts, having been started in this manner, continue to their neutral positions and the notch 193 in the lower arm 192 seats again on the pin 173 (the notch 193 of the arm 191 having been already seated). When the pin 197 moves back to the left under extension of the spring 203, it cannot again immediately reengage either notch 196, since the relationship between the pin 173 and arms 191 and 192 is such as to prevent that result, as will be clear from Figure 6. The relief valve 200 will operate in this manner to unlatch the control lever and shut off the flow of oil to the cylinder 42 at any time during the stroke of the piston in the event that the load on the

rockshaft should exceed a certain maximum, or in case the implement being raised encounters an obstruction which prevents further upward movement. Thus, the relief valve 200 not only serves the purpose of immediately relieving the pressure in the supply duct 64 by discharging oil from the end of the passage 201, but also to center the control valve and thereby reducing the pressure in the entire system.

When the double acting remote cylinder 115 is in use, the control lever 183 does not move angularly as the piston moves in the cylinder, since non-use of the piston 39 effects immobility thereof and consequently immobilizes the link 184 and member 181; but the control lever 183 can nevertheless be latched in active position for movement of the piston in either direction, selectively. When the piston 117 reaches either end of the cylinder 116, however, the increase of hydraulic pressure in the system will cause the relief valve 200 to unlatch the latch mechanism and permit the spring 195 to center the operating arm 175 and valve 80.

Obviously, the pressure relief valve 200 is available at all times to relieve an excess pressure in the hydraulic system by releasing oil from the supply duct 64, regardless of whether or not the latching device is engaged or disengaged.

It is desirable, when making accurate adjustment of the implement associated with the tractor, that the fluid motor 40 operate at a slower rate of speed than when the implement is being raised to transport position. Hence, it is desirable to provide means for gradually increasing the pressure applied to the cylinder 42 by means of the control lever 183. For this purpose a bleed hole 220 is provided in the supply duct portion 68, and is adapted to register with a bleed duct 221 in the gear member 170, best shown in Figures 3 and 5. The bleed duct 221 extends radially inwardly from the cylindrical surface of the gear member 170 and extends axially of the latter and has an adjustable valve 222 in the end of the member 170. Beyond the seat of the valve 222, the duct 221 is in communication with the reservoir between the gear teeth of the member 170 and the valve 222 can be adjusted by a screwdriver inserted through an opening 223 in the side of the housing 60 in line with the valve member 222. A plug 224 normally closes the adjusting hole 223 against entrance of dirt and moisture. Thus, the valve 222 is adjusted to permit a sufficient amount of oil to leak or bleed from the high pressure duct 68, to reduce the hydraulic pressure in the latter and thereby cause the piston 39 to move more slowly in the cylinder 42. The aperture 220 and duct 221, however, are disposed in alignment only when the control lever 183 is at or near the neutral position, for by moving the lever 183 in a direction to apply pressure to the piston 39, the duct 221 is shifted angularly relative to the hole 220, to move them out of register, until the duct 221 is entirely out of register with the hole 220 when the control lever 183 is in its maximum raising position, whereupon full pressure is applied to the fluid motor 40 to obtain maximum speed from the latter.

The construction of the novel valve plunger 80 and associated parts, will now be described, in connection with Figures 9 and 10. The valve plunger 80 is hollow, being provided with an axially extending cylindrical passage 225, the outer ends of which have portions 226, 227 of

larger diameter for receiving the inwardly extending cylindrical portions 96 of the closure members 90, 91, respectively. Each of the inwardly extending cylindrical portions 96 of the closure members is provided with a peripheral groove 228, in which is disposed a resilient annular sealing member 229 adapted to slidably engage the inner surface of the associated passage 226 in the plunger 80 and prevent flow of fluid between the closure member and the end of the axial passage 225.

Disposed within the passage 225 is a piston member 233 which fits closely but slidably within the passage 225 and is provided with a pair of head portions 234 at opposite ends thereof, respectively, of larger diameter. The head portions 234 are slidably disposed within the end portions 226, 227 of the passage 225, of comparatively large diameter. The piston 233 is composed of two halves having a threaded joint 235 to facilitate assembly, and the piston 233 is provided with an axially extending bore 236 therethrough, disposed substantially coaxially with the passage 225 and plunger 80.

As explained herein before, the check valves 99, 100 have stems 98 which extend inwardly through passages 97 in the closure members 90, 91, respectively, and into the enlarged end portions 226, 227 of the passage 225, where the inner ends of the check valve stems 98 are adapted to be engaged by the adjacent ends of the piston 233, respectively. The piston 233 is provided with radially extending passages 237, 238 at the inner end of the enlarged head 234. The passages 237, 238 communicate with the axial bore 236. Near each end of the valve member 80 is disposed an annular port 239, 240 extending around the inner surface of the enlarged end portions 226, 227 of the passage 225. The ports 239, 240 are provided with openings which communicate with the valve cylinder 17 at points within the reduced diameter portions 81, 82 of the valve plunger 80.

The operation of the valve mechanism just described, will be explained in connection with the double acting cylinder 115. Figure 9 shows the valve mechanism disposed with all parts in neutral or inactive position. The valve plunger 80 is centered within the valve cylinder 17 and the piston 233 is centered within the valve plunger 80. It will be noted that there is a small clearance between each end of the piston 233 and the inner end of the adjacent check valves 99 and 100. Each of the annular ports 239, 240 is closed by the adjacent head 234 of the piston 233. In this position of the valve, the hydraulic fluid flows through the branches 69, 70 of the supply duct, along the reduced diameter portions 81, 82, of the plunger, and returns to the reservoir through the exhaust ports 73, 74. Now assume that the control lever 183 is shifted forwardly to raise the valve member 80 to direct the oil through the lower connector 133 and hose 129 to the cylinder 116. The valve plunger 80 is moved upwardly carrying with it the piston 233 until the end of the latter engages the inner end of the stem 98 of the check valve 99. As the plunger 80 is moved slightly upwardly the inner edge of the spool portion 85 closes the exhaust port 74, while the edge of the intermediate spool portion 84 closes the intake port 71. This causes pressure to build up in the branch duct 70, the cylinder supply port 76, the by-pass duct 110, and in case there is any air or vapor in the remote cylinder 115 or its hose connections, the fluid flows through the check valve 100 and compresses the air or gas in the

cylinder, for it will be noted that the check valve 99 has not yet been opened and therefore the fluid has not yet been released from the cylinder 160. Thus, it will be evident that the pressure in the hydraulic system builds up to the value necessary to open the pressure relief valve 200, and this pressure is applied to the outer side of the check valve 99 tending to hold the latter closed. Therefore, it is necessary to overcome this pressure in order to open the check valve 99 and permit the fluid motor 115 to begin operation. If the check valve 99 were to be opened manually through the control lever 182, it would require considerable effort on the part of the operator, but according to the principles of the present invention, this is accomplished hydraulically to relieve the operator.

This is accomplished by shifting the valve plunger 80 slightly farther upwardly, and since the piston 233 is in abutment with the end of the stem 98 of the check valve 99, the plunger 80 can be moved relative to the piston 233 until the annular port 240 is uncovered by moving it beyond the inner edge of the adjacent piston head 234. The valve parts are now in the position illustrated in Figure 10. Oil under pressure now flows through the annular port 240 and through the radial passage 238 into the inner bore 236 of the piston 233, and into the enlarged space 227 between the closure member 91 and the adjacent piston head 234. The pressure in the space 227 is now equal to the pressure of the oil on the head of the check valve 99, but it will be noted that the area of the end of the head 234 of the piston 233 is appreciably larger than the area of the head of the check valve 99, and therefore the total pressure against the piston tending to open the check valve 99 is greater than the pressure resisting the opening of the check valve, with the result that the piston 233 and check valve 99 begin to move upwardly. The fluid does not run out of the other end of the inner bore 236 into the space 226 between the closure member 90 and the upper end of the piston 233 for the reason that the inner end of the stem 98 of the check valve 99 closes the upper end of the bore 236 and prevents passage of oil therethrough.

As the piston 233 and check valve 99 move upwardly the inner edge of the lower piston head 234 cuts off the fluid flow through the annular port 240, thereby stopping the opening movement of the upper check valve 99. The valve parts are now in the position illustrated in Figure 11 with the annular port 240 closed and the check valve 99 cracked open. Attention is called to the fact that the upper annular port 239 is not quite closed by the upper piston head 234 so that there is no hydraulic lock to prevent upward movement of the piston 233 in the passage 225. Hence, it is evident that the check valve 99 can be opened in as small increments of movement as desired, which are controlled by the increments of movement of the valve plunger 80 which is under the manual control of the operator. Since the entire pressure necessary to open the check valve 99 acts against the lower head 234 of the piston 233 and reacts against the inner end of the lower closure member 91, there is substantially no effort required by the operator to open the valve 99. As the operator continues to move the valve plunger upwardly, the piston 233 is moved upwardly to raise the check valve 99 whenever the lower annular port 239 is uncovered by the piston head 234 to permit fluid to flow through the radial aperture 238, the inner bore 236 into the

space 227, but as soon as the piston head 234 covers the annular port 240 the upward movement stops.

Of course, as soon as the check valve 99 is cracked open, the pressure on the head of the valve 99 is relieved, so that the last part of the opening movement will require very little fluid pressure to open the valve. Figure 12 shows the various parts of the valve in the position just before the check valve 99 is completely open. The plunger 80 has been moved to its final position, while the piston 233 is just moving upwardly to close off the annular port 240 to stop the movement of the valve 99 at its wide open position.

Figures 9 and 10 also show the action of the bleed duct 221 as it shifts angularly out of register with the opening 220. Figure 10 shows the bleed duct 221 is partly blocked when the check valve 99 is ready to open, and it will be completely shut off when the check valve 99 is wide open.

When the control lever 183 is brought back to neutral position, the valve plunger 80 is centered, the check valve 99 being returned to its seat by the spring 105. The valve mechanism operates in a manner similar to that described above when the valve plunger 80 is shifted downwardly to move the fluid motor 115 in the opposite direction, since the valve plunger 80, piston 233, check valves 99, 100 and the valve cylinder 77 and associated passages are symmetrical at both ends. Briefly, when the plunger 80 is shifted downwardly, the piston 233 engages the inner end of the stem 98 of the lower check valve 100, closing off the lower end of the inner bore 236, while the fluid is applied under pressure to the annular port 239 and exerts a downwardly acting force against the upper piston head 234 within the space 226 to shift the piston 233 downwardly to open the check valve 100.

It will be apparent that numerous modifications, substitutions, and rearrangements may be made without departing from the essence of the invention.

What is claimed as the invention of said Frank T. Court, deceased, and desired to secure by Letters Patent is:

1. In hydraulic mechanism, the combination of a fluid conduit, a fluid pressure motor connected thereto, a valve for controlling the flow of fluid to said motor and including a valve member shiftable between an inactive position in which pressure in said duct is relieved and an active position in which fluid is directed under pressure to said motor, means biasing said valve member toward said inactive position, disengageable latching means for holding said valve member in said active position and including a pair of shiftable cooperative latching elements, one of which is connected with said valve member, an excess pressure relief valve associated with said conduit and including a movable valve member and biasing means for holding said member in closed position against the pressure in said conduit, the other of said latching elements being mounted on said relief valve member for shifting movement out of latching engagement responsive to an increase of fluid pressure above a predetermined value, thereby permitting said first mentioned biasing means to return said valve member to inactive position.

2. In hydraulic mechanism, the combination of a fluid pressure motor, a supply duct therefor, a valve in said supply duct for controlling the flow of fluid from said duct to actuate said motor

in either of two relatively opposite directions, selectively, and including a valve member shiftable from an intermediate inactive position in either direction to a pair of active positions, means controlling said valve member comprising a control arm shiftable angularly about an axis, and means for biasing said valve member toward said inactive position comprising a pair of arms pivotally mounted on said control arm, stop means mounted on said control arm in a position to be straddled by said pair of arms, a normally stationary element mounted adjacent said control arm and adapted to be straddled by said pair of arms, and biasing means urging said pair of arms in gripping engagement with said stop means and said stationary element.

3. In hydraulic mechanism, the combination of a fluid pressure motor, a supply duct therefor, a valve in said supply duct for controlling the flow of fluid from said duct to actuate said motor in either of two relatively opposite directions, selectively, and including a valve member shiftable from an intermediate inactive position in either direction to a pair of active positions, means controlling said valve member comprising a control arm shiftable angularly about an axis, and disengageable latch means for retaining said valve member in either of said active positions and for biasing the same toward said inactive position comprising a pair of arms pivotally mounted on said control arm outwardly of said axis, stop means mounted on said control arm in a position to be straddled by said pair of arms, a normally stationary element mounted adjacent said control arm, said pair of arms straddling both said stop means and said normally stationary element, and having biasing means urging said pair of arms in opposed gripping engagement therewith, each of said pair of arms having means alternatively engageable with said stationary element when said control arm is shifted in either direction to position said valve member in either of said active positions.

4. In hydraulic mechanism, the combination of a fluid pressure motor, a supply duct therefor, a valve in said supply duct for controlling the flow of fluid from said duct to actuate said motor in either of two relatively opposite directions, selectively, and including a valve member shiftable from an intermediate inactive position in either direction to a pair of active positions, means controlling said valve member comprising a control arm shiftable angularly about an axis, and disengageable latch means for retaining said valve member in either of said active positions and for biasing the same toward said inactive position comprising a pair of arms pivotally mounted on said control arm outwardly of said axis, stop means mounted on said control arm in a position to be straddled by said pair of arms, a normally stationary element mounted adjacent said control arm on means shiftable responsive to an increase of pressure in said supply duct above a predetermined value, said pair of arms straddling both said stop means and said normally stationary element, and having biasing means urging said pair of arms in opposed gripping engagement therewith, each of said pair of arms having means alternatively engageable with said stationary element when said control arm is shifted in either direction to position said valve member in either of said active positions, either of said engageable means being disabled by shifting movement of said element to permit said biasing means acting through said pair of arms

to return said control arm and valve member to said intermediate inactive position.

5. In hydraulic mechanism, the combination of a fluid pressure motor comprising an extensible cylinder and piston assembly, a control valve therefor including a member shiftable in relatively opposite directions from an intermediate neutral or inactive position to a pair of active positions effecting extension and contraction of said cylinder and piston assembly, respectively, means controlling said valve member comprising a control arm shiftable angularly about an axis, a lever connected to said control arm for shifting the latter, a support on which said lever is swingably mounted, means rotatably supporting said support, means connecting said support to said motor to be rotated thereby to shift said lever by movement of said cylinder and piston assembly while said lever is in either of said active positions in the same direction in which said lever is moved from said neutral position, disengageable latching means for retaining said lever and valve member in either of said active positions comprising a pair of arms pivotally mounted on said control arm, stop means mounted on said control arm in a position to be straddled by said pair of arms, a normally stationary element mounted adjacent said control arm and adapted to be straddled by said pair of arms, biasing means urging said pair of arms in gripping engagement with said stop means and said stationary element and limit stop means engageable with said lever during movement thereof in either direction by movement of said support, thereby disengaging said latching means and permitting said valve member to be shifted to said neutral position by said biasing means acting through said pair of arms.

6. In hydraulic mechanism, the combination of a fluid pressure motor comprising an extensible cylinder and piston assembly, a control valve therefor including a member shiftable in relatively opposite directions from an intermediate neutral or inactive position to a pair of active positions effecting extension and contraction of said cylinder and piston assembly, respectively, means controlling said valve member comprising a control arm shiftable angularly about an axis, a lever connected to said control arm for shifting the latter, a support on which said lever is swingably mounted, means rotatably supporting said support, means connecting said support to said motor to be rotated thereby to shift said lever by movement of said cylinder and piston assembly while said lever is in either of said active positions in the same direction in which said lever is moved from said neutral position, disengageable latching means for retaining said lever and valve member in either of said active positions and for biasing the same toward said inactive position comprising a pair of arms pivotally mounted on said control arm outwardly of said axis, stop means mounted on said control arm in a position to be straddled by said pair of arms, a normally stationary element mounted adjacent said control arm, said pair of arms straddling both said stop means and said normally stationary element, and having biasing means urging said pair of arms in opposed gripping engagement therewith, each of said pair of arms having means alternatively engageable with said stationary element when said control arm is shifted in either direction to position said valve member in either of said active positions and limit stop means engageable with said lever dur-

ing movement thereof in either direction by movement of said support, thereby disengaging said latching means and permitting said valve member to be shifted to said neutral position by said biasing means acting through said pair of arms.

7. In hydraulic mechanism, the combination of a fluid pressure motor comprising an extensible cylinder and piston assembly, a control valve therefor including a member shiftable in relatively opposite directions from an intermediate neutral or inactive position to a pair of active positions effecting extension and contraction of said cylinder and piston assembly, respectively, means controlling said valve member comprising a control arm shiftable angularly about an axis, a lever connected to said control arm for shifting the latter, a support on which said lever is swingably mounted, means rotatably supporting said support, means connecting said support to said motor to be rotated thereby to shift said lever by movement of said cylinder and piston assembly while said lever is in either of said active positions in the same direction in which said lever is moved from said neutral position, disengageable latching means for retaining said lever and valve member in either of said active positions and for biasing the same toward said inactive position comprising a pair of arms pivotally mounted on said control arm outwardly of said axis, stop means mounted on said control arm in a position to be straddled by said pair of arms, a normally stationary element mounted adjacent said control arm on means shiftable responsive to an increase of pressure in said supply duct above a predetermined value, said pair of arms straddling both said stop means and said normally stationary element, and having biasing means urging said pair of arms in opposed gripping engagement therewith, each of said pair of arms having means alternatively engageable with said stationary element when said control arm is shifted in either direction to position said valve member in either of said active positions, either of said engageable means being disabled by shifting movement of said element to permit said biasing means acting through said pair of arms to return said control arm and valve member to said intermediate inactive position, and limit stop means engageable with said lever during movement thereof in either direction by movement of said support, thereby disengaging said latching means and permitting said valve member to be shifted to said intermediate inactive position by said biasing means acting through said pair of arms.

8. In hydraulic mechanism, a swingably mounted control valve operating arm, an excess pressure relief valve including a shiftable valve member and biasing means normally holding said member stationary, a pair of arms pivotally mounted on said operating arm, a stop mounted on said operating arm between said pair of arms, a normally stationary latch element secured to said relief valve and positioned between said pair of arms, and second biasing means urging said arms together in gripping relation to said latch element, said arms having recesses adapted to engage said element after said operating arm has been swung a predetermined amount in either direction, respectively, for yieldably holding the same, said element being disengageable from either of said recesses when said valve member is shifted against the pressure of said second biasing means.

9. In hydraulic mechanism, the combination of: a fluid pressure motor having a movable part; a control valve for the motor shiftable in relatively opposite directions between active and inactive positions, selectively, to effect starting and stopping of the motor part; a support movable relative to the motor and having connection to the motor part to be moved by movement of said part; a lever connected to the valve and carried by the support for movement independently of said support from an inactive position to an active position and return for shifting the valve, said lever further being movable with the support as the support moves with the motor part; means for retaining the lever in its active position, including releasable elements arranged to be overcome by force tending to return the lever toward its inactive position; limit means positionable to intercept the lever upon movement thereof to its active position while permitting movement of the support by the motor part relative to the lever, said limit means being so arranged relative to the lever and support that movement of the support after interception of the lever reverses the lever and applies such force as the aforesaid to release the elements of the retaining means; and means biasing the valve and lever to their inactive positions.

10. In hydraulic mechanism, the combination of: a fluid pressure motor having a movable along a linear path part; a control valve for the motor shiftable in relatively opposite directions between active and inactive positions, selectively, to effect starting and stopping of the motor part; a support movable relative to the motor about a journaling axis and having connection to the motor part to be moved angularly about said axis by movement of said part; a lever connected to the valve and pivoted on the support for movement independently of said support from an in-

active position to an active position and return for shifting the valve, said lever further being movable with the support as the support is moved angularly by the motor part; means for retaining the lever in its active position, including releasable elements arranged to be overcome by force tending to return the lever toward its inactive position; limit means positionable to intercept the lever upon movement thereof to its active position while permitting angular movement of the support by the motor part relative to the lever, said limit means being so arranged relative to the lever and support that continued angular movement of the support after interception of the lever reverses the lever and applies such force as the aforesaid to release the elements of the retaining means; and means biasing the valve and lever to their inactive positions.

VIRGINIA F. COURT,

20 Executrix of the Estate of Frank T. Court, Deceased.
